CLAIM

The ornamental design for an ombre artificial lash extension as shown and described.

DESCRIPTION

The file of this patent contains at least one drawing/photograph executed in color. Copies of this patent with color

drawing(s)/photograph(s) will be provided by the Office upon request and payment of the necessary fee.

FIG. 1 is a top left perspective view of an ombre artificial lash extension in accordance with the claimed design, shown in a first embodiment in the color green.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a top left perspective view of an ombre artificial lash extension in accordance with the claimed design, shown in a second embodiment in the color purple.

FIG. 9 is a front view of thereof.

FIG. 10 is a rear view thereof.

FIG. 11 is a left side view thereof.

FIG. 12 is a right side view thereof.

FIG. 13 is a top view thereof.

FIG. 14 is a bottom view thereof.

FIG. 15 is a top left perspective view of an ombre artificial lash extension in accordance with the claimed design, shown in a third embodiment in the color blue.

FIG. 16 is a front view of thereof.

FIG. 17 is a rear view thereof.

FIG. 18 is a left side view thereof.

FIG. 19 is a right side view thereof.

FIG. 20 is a top view thereof.

FIG. 21 is a bottom view thereof.

FIG. 22 is a top left perspective view of an ombre artificial lash extension in accordance with the claimed design, shown in a fourth embodiment in the color green.

FIG. 23 is a front view of thereof.

FIG. 24 is a rear view thereof.

FIG. 25 is a left side view thereof.

FIG. 26 is a right side view thereof.

FIG. 27 is a top view thereof.

FIG. 28 is a bottom view thereof.

FIG. 29 is a top left perspective view of an ombre artificial lash extension in accordance with the claimed design, shown in a fifth embodiment in the color purple.

FIG. 30 is a front view of thereof.

FIG. 31 is a rear view thereof.

FIG. 32 is a left side view thereof.

FIG. 33 is a right side view thereof.

FIG. 34 is a top view thereof.

FIG. 35 is a bottom view thereof.

FIG. 36 is a top left perspective view of an ombre artificial lash extension in accordance with the claimed design, shown in a sixth embodiment in the color blue.

FIG. 37 is a front view of thereof.

FIG. 38 is a rear view thereof.

FIG. 39 is a left side view thereof.

FIG. 40 is a right side view thereof.

FIG. 41 is a top view thereof; and,

FIG. 42 is a bottom view thereof.

The broken lines consisting of evenly spaced lines in the figures show portions of the ombre artificial lash extension that form no part of the claimed design. The ombre artificial lash extension is shown with symbolic breaks in its length. The appearance of any portion of the article between the break lines forms no part of the claimed design.
